UNITED STATES PATENT OFFICE

JOSEPH F. SULLIVAN, OF ARCHBALD, PENNSYLVANIA

GAS DISTRIBUTION APPARATUS

Application filed February 23, 1929. Serial No. 342,006.

The present invention relates to a combined gas collecting member and vent and has for its prime object to collect gas travelling along the outside of a gas pipe leading into a dwelling or the like and allow the escape of this gas into the atmosphere thus preventing it from entering into the house.

It is well known that gas escaping from a gas main tends to travel along the exterior surface thereof and some of the gas continues along the taps therefrom leading into houses and the like and eventually gets into the houses and often causes disastrous results such as asphyxiation of persons, explosions and the like. With this structure such results are effectively prevented.

Another very important object of the invention resides in the provision of an improved structure of this nature which is exceedingly simple in its construction, inexpensive to manufacture, thoroughly efficient and reliable in use and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the construction embodying the features of my invention showing the same in use,

Figure 2 is an end elevation thereof,

Figure 3 is another end elevation thereof opposite to that taken in Figure 2,

Figure 4 is a vertical sectional view thereof taken substantially on the line 4—4 of Figure 2, and

Figure 5 is a vertical sectional view taken substantially on the line 5—5 of Figure 4.

Referring to the drawing in detail it will be seen that the letter T denotes generally a gas collecting member including a frustoconical body 5 flared outwardly at the larger end thereof as is indicated at 6 and having the smaller end thereof closed by a plate 7. A foot 8 is formed at the larger end of

the body 5 to rest on the ground and a flange 9 is disposed about the body adjacent the smaller end thereof to form a leg for supporting this end and also for forming a baffle. A nipple 10 is formed integrally on the smaller end of the body 5 to radiate outwardly therefrom and to allow the escape of gas upwardly therefrom.

A vent pipe 11 is engaged with the nipple 10 by means of a union 12 or in any other suitable manner and this vent pipe extends up through the ground terminating in the atmosphere. A gas conduit 14 extends through the plate 7 and terminates at one end a spaced distance from the larger end of the body 5.

A screen 15 is formed in the body 5 about the conduit 14. It is preferable to provide a block or the like 17 in the ground, although this is not necessary, on which the foot 8 and the flange 9 rests. A gas pipe 18 leading from the gas main 19 is coupled with the end of the conduit 14 within the body 5 by means of a union 20 or the like.

A pipe 20' is coupled with the outer end of the conduit 14 by means of a union 21 or the like and leads through the wall 22 of a dwelling, house or the like to furnish gas for the usual well known purposes.

Now from the above detailed description it will be seen that should any gas be passing along the surface of the gas main 19 and travel along the outside surface of the gas pipe 18 said gas will be trapped in the gas collecting member T and will be allowed to escape out through the nipple 10 and pipe 11 to the atmosphere rather than to continue on into the dwelling. It will also be seen that the flange 9 functions as a baffle to deflect any gas which may be clinging along the outer surface of the body 5.

The screen 15 prevents the gas collecting member from filling with dirt when the ditch in which the piping and gas collecting member and the like are placed has been filled in.

I appreciate that I am not the first in the art to provide a device having the same general characteristics as that thus far described but I claim certain detail structural features

and improvements to enhance the efficiency, reliability, simplicity and durability of the structure.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

A gas distribution system including in combination; a gas distributing main, a gas collecting member formed from a frustoconical body having its smaller end closed by a plate and its larger end opened and flared outwardly, a foot on the periphery of the larger end of said body, a flange on the outside of said body at the smaller end thereof, said flange and said foot functioning as supporting means, a gas conduit connected to the distributing main and extending through said gas collecting member, a screen disposed at the larger end of said body and surrounding said conduit, and a vent pipe for leaking gas rising from the body in communication with the interior thereof adjacent the smaller end of said body.

In testimony whereof I affix my signature.

JOSEPH F. SULLIVAN.
